F. CRIESI.
WALKING TOY.
APPLICATION FILED DEC. 12, 1918.

1,311,553.

Patented July 29, 1919.

UNITED STATES PATENT OFFICE.

FRANK CRIEST, OF SHARPSVILLE, PENNSYLVANIA.

WALKING TOY.

1,311,553.

Specification of Letters Patent. Patented July 29, 1919.

Application filed December 12, 1918. Serial No. 986,454.

To all whom it may concern:

Be it known that I, FRANK CRIEST, a citizen of the United States, at present residing at Sharpsville, in the county of Mercer and State of Pennsylvania, have invented a new and useful Improvement in Walking Toys, of which the following is a specification.

The present application has reference to 10 improvements on my previous patents, Numbered 1,269,056 and 1,272,629, of June 11, 1918, and July 16, 1918, respectively, and seeks to provide, in connection with the simple and inexpensive toy representation of a 15 doll, bird, dog or similar animal, fowl or manikin of different styles, a means for turning the head thereof from side to side and in such toys so constructed as to provide for turning of the head and simultaneous 20 wagging of the tail.

This operation is performed by simple and inexpensive mechanism operated from and in connection with the mechanism utilized in my previous, above mentioned patents, for 25 effecting the automatic walking of the toy as it is pulled over the floor and is so constructed and applied that it is practically impossible for a child to break the same or render it inoperative by the ordinary rough 30 treatment to which all toys, more or less, are subjected.

Should the device by any extreme usage be rendered inoperative, the construction of the same is such that anyone, even though their 35 knowledge of tools is very limited, may readily and without expense supply a substitute for the broken part and thereby give new life to the toy.

With other objects in view that will hereinafter appear; my invention embodies certain improved features of construction and novel arrangement of parts, all of which will be described in detail, specifically pointed out in the appended claims and illustrated 45 in the accompanying drawings, in which:

Figure 1 is a rear perspective view of a skeleton or manikin which, when finished, may be the toy representation of a monkey or like upstanding animal.

50 Fig. 2 is a detail cross section taken substantially on the line 2—2 on Fig. 3 and illustrates the application of the invention to a dog or other four legged animal.

Fig. 3 is a side view and part section and 55 illustrates the invention as applied to a dog or similar quadruped and clearly shows the

connection of the parts to affect the simultaneous walking, head turning and tail wagging operations.

Fig. 4 is a detail perspective view, parts 60 separated, of the mechanism which constitutes the improved features of my invention.

In the drawings in which like numerals indicate like parts in all the figures, 1 represents a body which may be that of a monkey 65 or similar animal and includes the usual head 2, shoulders 3 and arms 4. The legs 5 which operate to represent and effect the walking of the toy, are operated by pushing or pulling the toy across the floor or table 70 and the alternate movement of the legs is effected by a rocker arm 6 pivoted, as at 7, to the lower portion of the body.

All of this construction, which works to effect the walking of the toy is the subject 75 matter of my aforementioned patents and forms, *per se*, no part of this present application, except that which is found necessary to make the present invention practical.

The rocker arm 6 includes a squared 80 socket 60, to take onto the squared lower end 26 of the head operating shaft 20 and the same is positively held thereto and against being pulled through the top by a screw and washer connection 8, an aperture 85 28 being provided in the lower end of the said shaft therefor.

The shaft 20 extends upward through the bore 10 in the body 1 and is, in any suitable manner, permanently fixed in the socket 21 90 provided therefor in the movable head 2.

This head connection may consist of a round shaft end glued or otherwise fixed in a round socket or a squared head end wedged or otherwise fixed in a square socket. 95

Affixed into a threaded socket 61 provided therefor in the rocker arm 6 is a tail member 9 adapted to rock therewith.

From the foregoing, it will be seen that, when the rocker arm operates to effect the 100 step by step movements of the legs in walking, it rocks or rather wags the tail of the animal and, by connection through the shaft 20 with the head, operates to simultaneously rock said head.

This rocking of head and wagging of tail goes on so long as the toy is pushed or pulled across the floor or table and it is readily understood that, when such action ceases, the rocker arm comes to rest and consequently also the mechanism operative therefrom. 110

In the case of a toy representing animals of the quadruped family, the head is rocked or oscillated by the rocker arm operating the fore legs while the wagging of the tail is accomplished by the rocker arm operating the rear legs. In this case, the rear rocker arm operates a short shaft 11, loosely mounted in a bore 11^a, and whose upper squared end 12 is fitted into a socket in a tail member 13, sidewise movable in a cut out portion 14 provided therefor in the body 1.

In the case of representations of animals of the biped family, the head and tail of the toy being operated by the same rocker member, oscillate in the same way, that is on the same line through the center of the figure, while in the case of the representation of quadrupeds, the rocker arms being separate for the fore and rear legs and connected by cross rods 15 to make them rock in opposite direction with relation to each other, if the head is turned to the left (indicating a step forward with the right fore leg), the tail member will rock to the left also, since the particular cross arm 15 connecting with the right side of the fore rocker connects with the left side of the rear rocker arm, thereby rocking the same in a different direction with respect to the other. Thus in the case of quadruped toys, the head and tail rock to the same side alternately and not in the same line through the body, as in the case of biped representations.

What I claim is:

1. A toy embodying a pair of legs adapted to frictionally engage a base and so connected to the body as to permit the forward and backward swinging thereof, a rocking device mounted on the body and

having its opposite ends held in engagement with the legs, whereby as the body is drawn along, the oscillation of the said device operates to swing the legs oppositely, and mechanism connected to the said rocking device to simultaneously cause the oscillation of another member of the toy.

2. A walking toy embodying a pair of legs adapted to frictionally engage a base and so connected to the body as to permit the forward and backward swing thereof, the said body including a head and a tail member, a rocking device mounted on the body and having its opposite ends held in engagement with the legs, whereby, as the body is drawn along and the movement of alternate ones of the legs is retarded by reason of frictional contact with the base, the oscillation of the said device operates to swing the other leg oppositely, and mechanism connected to the said rocking device to simultaneously cause the oscillation of the head and tail member, as the legs assume the walking action.

3. A walking toy that includes a body having head and tail members, a pair of legs adapted to frictionally engage a base and pivotally connected to the body to swing backward and forward relatively to the said body and adapted to project in the walking direction of the toy, means coöperating with the body and the legs for imparting a reverse movement to one leg as another leg moves forward, as the body is pulled forwardly or backwardly, and devices connected with the means that impart reverse movement to the legs for effecting movement of the head and the tail member.

FRANK CRIEST.
